HEADREST

Samuel R. Jones, Cave Creek, Ariz.
Application June 30, 1954, Serial No. 31,247

Term of patent 14 years

(Cl. D15—2)

Fig 1

Fig. 1 is a perspective view of a headrest showing my design.

Fig. 2 is a plan view of the headrest shown in Fig. 1.

Fig. 3 is a side elevation of the headrest shown in Fig. 1.

Fig. 4 is an end elevation of the headrest shown in Fig. 1.

I claim:

The ornamental design for a headrest, as shown.
